United States Patent Office.

THOMAS L. RIVERS, OF NEWARK, NEW JERSEY.

Design No. 4,355, dated September 13, 1870.

DESIGN FOR CLAMP FOR TRUNK-CORNERS.

The Schedule referred to in these Letters Patent and making part of the same

To all whom it may concern:

Be it known that I, THOMAS L. RIVERS, of Newark, in the county of Essex and State of New Jersey, have invented a new and useful Improvement in Designs for Clamps for Corners of Trunks; and I do hereby declare that the following is a full, clear, and exact description of the configuration thereof, reference being had to the accompanying drawing making a part of this specification, in which—

Figure 1 is a perspective view.

Figure 2 is a section, taken in the plane $x\ x$ of fig. 1.

Like letters in both figures of the drawing indicate like parts.

My invention relates to the class of clamps for protecting the corners of trunks from injury during the handling or transportation thereof, and consists in forming a series of convexities over and around the corner of the clamp, so as to give it a more ornamental appearance, as well as greater strength and durability.

These convexities consist of a slight convexity, *a*, formed immediately over the corner of the clamp, and then terminating in a larger convexity, *b*, on each side thereof, thus producing a corrugated or uneven surface across the corner, which not only gives the clamp an ornamental appearance, but greater strength, rendering it less liable to break.

Having thus fully described my invention,

What I claim therein as new, and desire to secure by Letters Patent, is—

The design for clamps for trunk-corners, substantially as herein shown and described.

As evidence that I claim the foregoing as my invention I have hereunto set my hand in the presence of two witnesses.

T. L. RIVERS.

Witnesses:

CHAS. F. MYERS,
J. F. OLSTEAD.
